ALFRED G. HAGUE, OF DES MOINES, IOWA, ASSIGNOR TO ROLLINS HOSIERY MILLS, OF DES MOINES, IOWA, A CORPORATION OF IOWA

NEEDLE FOR REPAIRING RUNS IN KNITTED FABRICS

Application filed May 10, 1927. Serial No. 190,250.

My invention relates to that class of needles in which there is employed a hook and a pivoted latch which cooperates with the hook, and which, when in use, at times closes 5 the hook and at other times assumes a position at its limit of movement away from the hook.

My object is to provide means of simple, durable and inexpensive construction, where- 10 by during the normal operation of the needle the said latch is at the proper instant positively and forcefully moved from its closed to its open position, and in which lat- 15 ter position it is yieldably held against acci- dental displacement in proper position to be engaged by the thread which returns it to closed position.

My invention consists in the construction, arrangement and combination of the various 20 parts of the device, whereby the objects contemplated are attained, as hereinafter more fully set forth, pointed out in my claims, and illustrated in the accompanying drawings, in which:

25 Figure 1 is a side elevation of my improved needle, a portion being broken away to show the manner in which the pivoted latch is mounted therein.

Figure 2 is a side elevation of the lower 30 end of the needle showing the latch in a partially open position.

Figure 3 is a side elevation of the lower end of the needle showing the latch in a closed position.

35 Figure 4 is a detail sectional view taken on the line 4—4 of Figure 3.

My improved needle comprises a body portion 10 mounted in a suitable handle 11. The lower end of the body portion 10 termi- 40 nates in a hook 12. The body portion 10 is provided with a slot 13 extending between its back and front edges. Said slot 13 is a slight distance above the hook 12. The upper edge of the slot 13 terminates in an upwardly and 45 outwardly extending portion 14, and also an upwardly and outwardly extending portion 15, the upper end of which terminates in a notch 16. Pivoted within the groove 13 is a latch 17 by means of a pivot 18. The inner 50 end of the latch 17 is formed circular, said

circular portion having an outwardly projecting lug 19. The latch is tapered toward its outer end in the manner clearly illustrated. The outer end of the latch is designed to overlap the free end of the hook 12 when closed, in the manner clearly illustrated in Figure 3, and is adapted to be supported within the upwardly and outwardly inclined portion 14 of the groove 13 when in its open position. The free end of the latch projects 55 slightly forwardly of the front edge of the member 10.

Supported within the notch 16 is a spring 20, which extends downwardly into the grooves 15 and 13 and is provided at its lower end with an inwardly curved portion 21. The spring is designed to normally rest in the position shown in Figure 2 against the shoulder 22 formed in the body portion 10, so that when the latch 17 is moved from the position shown by dotted lines to the position shown by solid lines in Figure 2, it will be free of the spring 20, and its inner edge brought into engagement with the free end of the curved portion 21 as the latch is moved from the position shown in dotted lines in Figure 2 to the closed position shown in Figure 3. After the latch is released after being brought to the said closed position, its free end will be thrown upwardly and will be moved to the position shown in Figure 1, said latch being frictionally retained in the last said position by the lug 19 engaging the inner edge of the spring 20 as it moves from the position shown by solid lines in Figure 2 to the position shown in Figure 1. The latch is carried 70 through this last movement by its momen- 75 tum.

The needle is operated by causing the hook 12 to enter the last loop 23 of the run, the needle being forced downwardly through the loop until it has reached the point above the upper end of the latch 17 and the position illustrated in Figure 1. The needle is then moved upwardly and slid through said loop, the forward edge of the loop engaging the upper end of the latch 17, and causing the same to be forced downwardly. A new thread 24 is caused to enter the hook 12 on the upward movement of the needle. This 80 85 90 95 100

upward movement is continued until the latch 17 has been moved to a closed position, and the said latch and hook 12, together with the thread 24, are pulled upwardly through said run, thus forming a new loop. As the 5 loop 23 passes over the end of the latch 17 and disengages the same, the spring 20 forces the latch 17 upwardly to the position shown in Figure 1, after which a new stitch may be 10 made in the manner above described.

It will be seen that as the needle is moved upwardly and the upper end of the latch 17 is caused to engage the loop 23, a slight amount of power is required to disengage the lug 19 15 from the spring 20. This is easily accomplished, however, due to the sharp inclination between the upper edge of the latch 17 and the loop, but as the needle is moved upwardly to the position shown in Figure 2, it 20 will then be seen that the angle of movement between the latch and the loop is substantially at right angles to the upper edge of the latch. It is desirable that the lug 19 be caused to disengage the spring 20 at this point to permit 25 free movement of the latch from the position shown by solid lines to the position shown by dotted lines in Figure 2. Otherwise, the threads will be broken by the upward movement of the needle. After the latch has 30 reached the dotted position it will then be seen that the upper edge of the latch is again inclined to the line of movement, so that considerable leverage is provided to act against the spring 20, as the latch is moved to its 35 closed position.

It is further essential that the latch have free movement, as above described, due to the fact that that portion of the needle in which the pivot 18 is mounted is usually considerably swelled or broadened, which increases 40 the tension on the loop 23 as the needle is passed through the same.

By providing the spring 20, I have provided means whereby the speed in the operation 45 of the needle is greatly increased. Great difficulty has heretofore been experienced in feeding the needle downwardly between the threads to be taken up, as the pivoted latch usually catches and tangles with the threads.

50 By providing the spring, the latch is automatically thrown to its open position and there held so that the knitting process is easily and quickly accomplished.

I claim as my invention:

55 1. A knitting needle comprising a handle terminating in a hook, the handle being provided with a central slot near the hook and between the forward and rear edges of said handle, a latch having one end pivotally 60 mounted in said slot and its other end adapted to cover the free end of said hook when in its closed position, a spring having one end mounted in the back edge of said slot and its other end curved inwardly to engage the inner edge of said latch at a point in front of the

pivot of said latch as the latch approaches a nearly closed position, and means for limiting the inward movement of the spring when disengaged from said latch to permit free movement of the latch through a larger portion of its swinging movement, the latch having an outwardly projecting lug designed to engage the spring just before the latch has moved to its maximum open position to yieldably retain the latch in said open position.

2. A knitting needle comprising a handle terminating in a hook, the handle being provided with a central slot near the hook and between its forward and rear edges, said slot terminating in an outwardly and upwardly inclined portion which in turn terminates in a notch, a latch having one end pivotally mounted in said slot and its other end adapted to cover the free end of said hook when in its closed position, a spring having one end mounted in said notch and its other end curved inwardly to engage the inner edge of said latch at a point in front of the pivot of said latch as the latch approaches a nearly closed position, the spring being designed to rest normally adjacent to the inclined portion of said slot to limit its inward movement when disengaged from said latch, to permit free movement of the latch through a larger portion of its swinging movement, the latch having an outwardly projecting lug designed to engage the spring just before the latch has moved to its maximum open position to yieldingly retain the latch in said open position.

Des Moines, Iowa, April 18, 1927.
ALFRED G. HAGUE.
